Primary Examiner—Theodore M. Shooman*Assistant Examiner*—Catherine Tuttle*Attorney, Agent, or Firm*—Dunlap & Coddng[57] **CLAIM**

The ornamental design for a spat wrap for cleated athletic shoes, as shown and described.

DESCRIPTION

FIG. 1 is a side elevational view of a spat wrap for cleated athletic shoes showing our new design, with a portion of a cleated athletic shoe and lower extremity of a leg in broken lines for illustrative purposes only and forming no part of the claimed design;

FIG. 2 is a side elevational view thereof;

FIG. 3 is a side elevational view thereof, opposite that shown in FIG. 2;

FIG. 4 is a front elevational view thereof;

FIG. 5 is a rear elevational view thereof;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7
